UNITED STATES PATENT OFFICE.

THOMAS F. FAY, OF DANBURY, CONNECTICUT.

FUR-BLOWING MACHINE.

SPECIFICATION forming part of Letters Patent No. 369,699, dated September 13, 1887.

Application filed January 24, 1887. Serial No. 925,283. (No model.)

To all whom it may concern:

Be it known that I, THOMAS F. FAY, a citizen of the United States, residing at Danbury, in the county of Fairfield and State of Connecticut, have invented certain new and useful Improvements in Fur-Blowing Machines; and I do hereby declare the following to be a full, clear, and exact description of the invention, such as will enable others skilled in the art to 10 which it appertains to make and use the same.

My invention relates to the class of machines especially adapted for use in picking and separating the different grades of fur required in the manufacture of hats. It is of course well 15 understood by those familiar with the art that the fur used in the manufacture of hats and similar articles is purchased in large quantities, different lengths, grades, and kinds of fur being mixed together and the entire mass filled 20 with dirt and other refuse. The machines employed for picking, cleaning, and separating the grades of fur consist ordinarily of a series 25 of chambers, of which any number may be used, each chamber containing a picker-cylinder, feed-apron, screen, and refuse-box. As heretofore constructed, these machines have delivered but two grades of fur, which has necessitated that a portion of the stock be passed 30 through the machine a number of times, as various grades of fur are required in the manufacture of hats. The time and labor required in properly grading the fur has thus formed a 35 very considerable element in the cost of production.

The object of my present invention is to so 40 construct and arrange the machine that the fur as purchased in the market will require to be run through but once, and will by this operation be separated into three, four, or any desired number of grades, depending upon the 45 number of chambers in the machine. In the present instance I have shown a machine containing six chambers, divided into two sections, and delivering three grades of fur, which fully illustrates the principle of my invention. It will of course be understood that the details 50 of construction of the machine, the shape, material, and putting together of the frame-work, &c., are not of the essence of my invention.

In order to accomplish the above-stated results I have devised the simple and novel construction of which the following description,

in connection with the accompanying drawing, is a specification.

The drawing is a central longitudinal section 55 of the machine.

1 denotes chambers, each of which is preferably provided with a window, 2.

Beginning at the right of the machine, 3 denotes a feed-apron carried by rollers 4 outside 60 of the machine, upon which the stock is placed, and by which it is carried to a picker-cylinder, 5, within the first chamber. The picker-cylinders are rotated at a high rate of speed, and act to tear the matted fur apart and to 65 throw the lighter portion thereof clear to the top of the chamber. This settles upon a second feed-apron, 3, carried by rollers in the same manner, and is carried by this apron to a similar picker-cylinder in the second chamber, 70 where the operation is repeated. The dirt, however, and heavier portions of the fur, instead of being thrown up by the picker-cylinders, drops down upon inclined screens or sieves 6. These screens are hinged in any suitable manner at the top and are continually agitated by rotating cams 7, which raise the screen 75 slightly and then allow it to drop back upon its supports. The dirt and heaviest portion of the refuse passes through the screen and 80 into a box or other receptacle, 8, under it. The portion of the fur or other material in each chamber that is not thrown up by the picker-cylinder and that does not pass through the screen passes over its surface and drops down 85 upon a return-apron, 9, carried by rollers in the same manner as the feed-aprons and passing along under the boxes, the motion of the return-apron being the reverse of that of the feed-aprons, and carrying the stock which is 90 delivered upon it back to the front of the machine and delivering it outside thereof in any suitable receptacle that may be provided. These return-aprons may be made to extend under two, three, or four of the chambers. In 95 practice I have found it best to divide the chambers into sets of three and provide a return-apron for each set, the machine, in fact, being thus divided into sections. The operation in the second chamber is the same as in the first. 100 The operation in the third chamber, likewise, is the same upon the fur as in the other chambers, the only differences being that a box or receptacle, 10, is provided either in the cham-

ber or under the machine, for a purpose presently to be explained, and the portion of the fur which settles upon the feed-apron within this chamber passes to another section of the 5 machine—that is, to another set of chambers. The operation in the fourth and fifth chambers, counting from the right—that is, the first and second chambers in the second section of the machine—is the same as in the first and second 10 chambers of the first section. The material in these chambers that does not drop upon the feed-aprons in said chambers or pass through the screens passes over the screens and drops upon a return-apron, 9, similar to 15 the one under the first section. This apron carries the material dropped upon it back toward the front of the machine and deposits it in box 10, a short apron, 11, carried by rollers 12, being provided to guide the material into 20 the box, it being compelled to pass between the two aprons. The material dropped upon the feed-apron in the sixth chamber, counting from the right of the machine—that is, the last chamber in the second section of the machine, as shown in the drawing—is carried out 25 of the machine and deposited in a box or suitable receptacle, which it was not deemed necessary to illustrate.

It will thus be seen that in the machine illustrated in the drawing the fur fed into it is separated into three grades. The first or finest grade will be that delivered by the feed-apron

from the last chamber of the second section. The next grade will be that delivered by the second return-apron into box 10, and the third 35 grade will be that redelivered at the front of the machine by the first return-apron. It will of course be understood that this principle may be carried out by adding as many sections as may be desired. If an additional section were 40 provided, the fur would be separated into four grades; if two additional sections were provided, into five grades. In practice I have often found it desirable to use twelve chambers, dividing the machine into four sections, 45 each provided with a return-apron, and thus producing five grades of fur by a single operation.

Having thus described my invention, I claim—

A fur-blowing machine consisting of two or more sections, each of which is provided with an independent return-apron, each of the said sections having two or more independent chambers, and each of the said chambers having a picker-cylinder, a feed-apron, and a screen, all combined to operate substantially as set forth.

In testimony whereof I affix my signature in presence of two witnesses.

THOMAS F. FAY.
